CAN CARRYING DEVICE

Keith W. Burge, Highland Park, Ill.

Application April 26, 1950, Serial No. 158,162

5 Claims. (Cl. 294—87.2)

1

The present invention relates to a carrier, and more particularly to an inexpensive carrying device for a plurality of cans or containers.

In analyzing the sales appeal of various products, and packaging and other factors, it has been found that sales are greatly increased if suitable packages are provided particularly in the instance of certain canned goods. It has been shown definitely that sales are stimulated where such products as tomato juice, fruit juice, beer and other beverages, which are put up in metal cans, are so arranged that the purchaser may conveniently pick up a plurality of cans with one hand.

One of the disadvantages of packaging however, is the total cost involved which includes the materials of which the package is made, and the labor required in order to fill the package with whatever is to be sold in packaged units.

More recently it has been found that six cans of liquid or beverage will sell more readily if the cans are placed in separate packages. The package merely serves as a convenient handling device from the shelf to the cart being pushed about the store in a self-service or super market. Thereafter, the package is placed in a larger container or packed along with other purchases and the package is of no value until the larger package again is unpacked at the home of the consumer. Thereafter, the package usually is discarded.

In order to minimize the cost involved including the increased cost of labor, it is proposed in accordance with the present invention, to provide a relatively simple carrier which will hold together a plurality of cans and which will not materially interfere with the normal shipping or packaging which is now customary in products of this kind.

In accordance with the present invention several variations are proposed, each of which is formed of relatively inexpensive paper or paper board. When the carrier has served its purpose, it may be discarded with a minimum of effort since it is not necessary to close the carrier or otherwise tear it apart as is the case with present boxes.

It is therefore, an object of the present invention, to provide an improved carrier which is simple and economical to manufacture and use.

A still further object of the present invention is to provide a convenient readily disposable paper or paper board carrying device for a plurality of metal containers.

Other and further objects of the present in-

2

vention subsequently will become apparent by referring to the following description taken in conjunction with the following drawings wherein:

Fig. 1 is a perspective view of a carrier constructed in accordance with plans of the present invention;

Fig. 2 is a view partially in cross-section as seen in the direction of the arrows along line 2—2 of Fig. 1;

Fig. 3 is a view as seen in the direction of the arrows 3—3 of Fig. 2;

Fig. 4 is a perspective view similar to Fig. 1 showing the arrangement of the components without the cans being in position;

Fig. 5 is a detailed view showing the manner in which the band or belt is engaged; by the handle member;

Fig. 6 shows a variation of the carrying device illustrated in the previous figures; and

Fig. 7 is a detailed view showing the interlocking construction of the handle carrying device of Fig. 6.

It will be seen that in Fig. 1 a carrier device has been illustrated which conveniently holds together in a single unitary package six cans 11, each of which has cylindrical side walls and a beaded top and bottom 12. More commonly, the beaded top 12 carries the technical name of chime top, or bottom.

In the arrangement illustrated, it will be seen that the front row of cans 11, 13, and 14, are engaged by a paper band or belt 15. The paper belt or band 15 engages the cans 11 and 14 immediately beneath the beaded upper edge or chime top 12. The can 13 has its beaded upper edge or chime resting upon the top or chime of the corner cans 11 and 14. The cans in the back row likewise are similarly arranged so that the corner cans 16 and 17 support the center can 18.

The band consists of an endless belt or tape of paper which is engaged by a paper board handle member 19. The handle member 19 has a handle portion 21, which has a suitable opening 22 for receiving the fingers of the hand. The opening 22 extends down to a line extending along the supporting edge 23 adjacent the outer extremities of the paper board carrying member 21.

From Fig. 2 it is still more evident that the center can, such as the can 18 is supported by the end cans 16 and 17. The upper chime of the can 16 however rests upon the edge 23 of the handle member 21. Likewise the endless belt 15 engages the cans 17 and 16 immediately beneath the upper beaded or chime portion.

The arrangement illustrated in Fig. 4 clarifies the manner in which the handle member 21, which is provided at each end with notches 24, engages the belt 15 to form a paper carrying device. In assembling the carrier, the belt 15 is placed about a plurality of cans and then the cans which are arranged in two rows are separated by the insertion of the handle. This action on the rows of cans produces a tension in the belt 15. The handle 21 subsequently may be moved upwardly to expose the handle aperture 22, whereupon the entire device is ready for carrying.

In utilizing a carrier of this kind, one of the principal difficulties usually given serious consideration is the matter of providing a carrier which will permit the containers to be stacked on the shelves and which also will not interfere with the present normal packaging methods.

In the case of tomato juice, malt beverages, and the like, it is of course known that the cans are usually packaged in units which are multiples of 12. The arrangement illustrated in Figs. 1 to 4 has in mind providing a smaller package of six cans. It of course will be appreciated that an even smaller package of four cans might be constructed in accordance with the principles outlined by the present invention.

Preferably the notch 24 which engages the endless belt 15 is so arranged that the upward movement of the handle member 21 causes the two rows of cans to be moved outwardly from each other and at the same time the notches 24 tend to push the belt 15 inwardly into the spaces between the two rows of cans. It also will be appreciated that the carrier illustrated is capable of carrying six cans which are provided with crown caps.

In another embodiment of the present invention such as illustrated in Figs. 6 and 7, it is proposed to employ a tape or band 15 which surrounds the six cans. The six cans however, are separated from each other by a carrier or handle member 31 preferably formed of paper board or light sheet material which has two cross members 32 and 33. The handle member 31 is provided with a plurality of notches 34, which are arranged for cooperation with other notches 35 in each of the cross members, such as the cross member 32. This arrangement is illustrated in Fig. 7.

In utilizing the carrier shown in Figs. 6 and 7, each of the upper edges of the cross members 32 and 33, together with the upper edge 36 of the handle 31, is arranged to engage the underside of the beaded top or chime of each of the cans, thus each of the cans supported by the carrying device illustrated in Figs. 6 and 7, is engaged at two different points underneath the bead or chime by the relatively stiff paper board structure comprising the handle 31 with its cross members 32 and 33. The cans furthermore are engaged by the endless belt 15 which surrounds all of the cans and holds them in position in the cubicles formed by the handle 31 and the cross members 32 and 33.

The endless belt 15 is so arranged that prior to the time that the handle 31 is raised upwardly, the belt 15 is reasonably tight about the cans. The subsequent insertion of the paper board separators 31, 32, and 33 places such tension upon the belt 15 that the cans are carried with adequate safety from place to place.

While for the purpose of illustration and description of the present invention, certain pre-

ferred embodiments have been shown in the drawings, it is to be understood that the invention is not to be limited thereby, since such variations are contemplated as may be commensurate with the spirit and scope of the invention as set forth in the accompanying claims.

I claim:

1. A carrier for two rows of metal containers, having cylindrical sides and beaded tops and bottoms, comprising a single band of flexible paper closely surrounding said cans immediately beneath their tops, a paper board handle arranged between said rows of cans to engage adjacent cans in opposite rows immediately beneath the top thereof, said handle having notches at the top edge for receiving said paper tape.
2. A carrier for six metal cans arranged in two rows, said cans having cylindrical sides and chime tops and bottoms, comprising a single continuous band of flexible paper closely surrounding said cans immediately beneath the chimes, a paper board handle arranged between said rows of cans to engage portions of the chimes of certain cans in opposite rows when moved upwardly, said handle member adjacent the exterior thereof having notches for receiving said paper band, said rows of cans being displaced by said handle when moved upwardly thereby to cause said tape to be tightened about said cans.
3. A carrier for two rows of cylindrical metal cans having beaded tops and bottoms comprising a single endless paper belt closely surrounding said rows of cans in the vicinity of their tops, a handle member of relatively stiff sheet material, said handle member being inserted and extending between said rows of cans to displace said rows to cause tension to be present in said belt, said handle member engaging the portions of the majority of the beaded tops of said cans whereby the said carrier may be used to lift said rows of cans.
4. A carrier for two rows of cylindrical metal cans having beaded tops and bottoms comprising a single endless paper belt closely surrounding said rows of cans in the vicinity of their tops, a handle member of relatively stiff sheet material positioned between and extending between said rows of cans, said handle member engaging portions of the beaded portions of the tops of the four corner cans whereby said handle member supports said cans and said carrier may be used for carrying said cans.
5. A carrier for two rows of cylindrical metal cans having beaded tops and bottoms comprising a single endless paper belt closely surrounding said rows of cans, in the vicinity of their tops, a handle member of stiff sheet material having two cross members carried thereby, said handle member and cross members being inserted between said rows of cans and between individual cans in said rows, thereby to displace said cans from their original positions to cause tension to be present in said belt, said handle and cross members engaging portions of the beaded tops of adjacent cans whereby said cans may be supported by said carrier.
